CLAIM

The ornamental design for a hanging air freshener with stacked oval shaped portions, as shown and described.

DESCRIPTION

FIG. 1 is a front and right side perspective view illustration of a hanging air freshener with stacked oval shaped portions.

FIG. 2 is a front view illustration thereof.

FIG. 3 is a bottom view illustration thereof.

FIG. 4 is a top view illustration thereof; and,

FIG. 5 is a right side view illustration thereof.

The left side view is a mirror image of the right side view.

The rear view is a mirror image of the front view.

1 Claim, 5 Drawing Sheets
